UNITED STATES PATENT OFFICE.

WILLIS K. HODGMAN, OF TAUNTON, MASSACHUSETTS.

MECHANICAL MOVEMENT.

SPECIFICATION forming part of Letters Patent No. 664,151, dated December 18, 1900.

Application filed January 21, 1898. Serial No. 667,393. (No model.)

To all whom it may concern:

Be it known that I, WILLIS K. HODGMAN, of Taunton, county of Bristol, State of Massachusetts, have invented an Improvement in 5 Mechanical Movements, of which the following description, in connection with the accompanying drawings, is a specification, like characters on the drawings representing like parts.

10 This invention relates to a mechanical movement which is particularly adapted for use in that type of printing-presses in which the "form" is carried by a bed having a reciprocating movement under the impression-cylinder, the bed being driven during the greater portion of its stroke by a rotating gear which meshes alternately with two parallel racks secured to the bed, a reversing device controlling the bed at each end of the 15 stroke and reversing its motion gradually while at high speed.

In another application, Serial No. 658,768, filed by me the 16th day of November, 1897, I have shown a novel reversing mechanism 25 comprising a rotating crank having a roller or stud which enters a straight guideway on a bracket movable with the bed, one of the sides of the guideway being movable to permit withdrawal of the crank roller or stud 30 from or its entrance between them, whereby cramping of the stud is prevented as the reciprocating mechanism begins or ends its control of the bed.

The movable side of the guideway may be 35 arranged to either swing out of the way of the crank-pin or it may move away from the opposite side of said guideway, as in my application referred to, the movement in either case being effected to enable the crank-pin 40 to freely move into or out of the guideway.

It will be obvious that the crank pin, stud, or roller, of cylindrical form in cross-section, presents a very small wearing-surface to engage the straight sides of the guideway, and 45 it is equally obvious that a square or polygonal stud having plane bearing-surfaces would be preferable on account of the greater wearing-surface which would be presented to engage the "shoe," as I will hereinafter term the 50 sides of the guideway. In order to make use of such a stud, however, it is necessary that the engaging surfaces thereof be kept at all

times in parallelism with the faces of the shoes; and it is the object of my present invention to provide means for utilizing a 55 crank-stud having plane engaging faces to co-operate with the shoes in a reversing mechanism.

Figure 1 is a cross-sectional view of a sufficient portion of a printing-press to be understood with one embodiment of my invention applied thereto. Fig. 2 is a left-hand side elevation of a portion of the mechanism shown in Fig. 1. Fig. 3 is an inner side view of the guide-box shown at the right of Fig. 1. 65 Fig. 4 is a transverse sectional view of my invention as applied to another form of bed-movement. Fig. 5 is a left-hand end elevation thereof, and Fig. 6 is a detail to be described.

Referring to Fig. 1, the side frame A², reciprocating bed A³, having parallel racks B and B', the co-operating gear G⁴ on the shaft F', the large gear E', fast on the driving-shaft E², the standard E⁴, gear E⁶, and cam G², fast 75 on the driving-shaft, may be and are substantially as in my said application referred to, corresponding parts having like characters of reference applied thereto. As shown in said application, a cam-plate B³ is rigidly secured to 80 the frame of the press and is provided with a cam-groove, (not shown,) which is entered by two crank-pins, one of which, as D², is shown in Figs. 1 and 2, said crank-pin being rigidly secured to a disk D, rotatable in a carrier-plate C², rigidly secured to the bed A³, 85 said carrier-plate being broken off, Fig. 2, to show the mechanism behind it, the shoe C, forming a part of said plate, being also broken out. It will be understood that the carrier C² has at its opposite end a similar shoe and that the second disk, similar to D, is mounted 90 therein.

A movable shoe C³ parallel to the shoe C² is provided with a horizontal pin or tongue 95 C⁵, which enters a longitudinal slot in the carrier-plate C², the disk D having a second crank-pin D⁴, which enters a vertical slot 20 (see dotted lines) in the body portion of the shoe C³. Remembering that the cam-plate 100 B³ is stationary, that the carrier-plate C² moves with the bed A³, and that the shoe C³ moves on and relatively to the carrier-plate it will be clear that rotation of the disk D

will operate through crank-pin D⁴ to move the shoe C³ toward or from its fellow-shoe C to thereby widen or narrow the guideway between them, all as in my said application.

- 5 In my present invention the crank-shaft F³ is made as a sleeve, rotatably mounted in bearings 2 and 4, Fig. 1, and having fast thereon a long pinion F² in mesh with and driven by the gear E⁶, while a loose collar G³ 10 on the sleeve engages the cam G² to effect longitudinal movement of the hollow shaft F³, said collar being held in place on the latter by fast collars 5 5. The sleeve F³ has fast thereon at its main end a crank-arm G⁵, on 15 the inner face of which are rotatably mounted two meshing pinions b c, the pinion b being secured to the end of a shaft b^x, extended through the sleeve F³ and into a bearing-box b', attached to the side frame A².
- 20 As shown in Fig. 3, the bearing-box has a square or polygonal hole b² to be entered by the correspondingly-shaped extremity b³ of the shaft b^x, preventing the latter from rotating, while permitting its longitudinal movement with the sleeve F³, a collar b⁴, fast on the shaft b^x, bearing against the outer end of the sleeve F³. The meshing pinion c is seated in a suitable recess in the crank-arm G⁵ and rotatable on a headed stud c^x, it being obvious that the movement of the pinion c around the fixed pinion b will effect axial rotation of said pinion c.
- 25 A rectangular actuating-block G⁶, having at its base an attached pinion g, is rotatably mounted on the crank-arm G⁵ by means of a stud g^x, the pinion being in mesh with the intermediate pinion c, so that when the crank-arm is rotated in the direction of arrow 12, Fig. 2, the pinion g and actuating-block G⁶ 30 will be rotated axially in the opposite direction. The pinion g is of the same diameter as the pinion b, hereinbefore referred to.

The axial rotation of the block G⁶ will have the effect of maintaining its parallel bearing-faces 7 and 8 in parallelism with the inner faces of the shoes C C³, so that the entrance or departure of said block from the guideway formed by the shoes will be readily effected by longitudinal movement of the hollow shaft 50 F³. It will be seen that the plane engaging faces of the block give extended wearing-faces, which tend to steadiness and accuracy of operation of the parts with increased power, and so long as the wearing-faces are maintained in proper position relative to the shoes their size may be increased as desired. When the bed arrives at the end of its reciprocation due to the rack and gear, the actuating-block G⁶ is in the vertical guideway and operates 60 to complete the stroke, gradually and rapidly reverse the direction of the bed, and return it to the point at which the rack-and-gear motion again comes into operation. The end of the movement of the actuating-block G⁶, 65 during which the bed is under the control of the reversing mechanism, is shown in Figs.

1 and 2. Now to enable the said block to easily enter between the shoes and also to leave it without cramping at the beginning and ending, respectively, of the control by the reversing mechanism one shoe is made movable relative to its fellow to get out of the path of the block by widening the space between them at such times and thereafter to be held in relatively-fixed position during 75 reversing or by a swinging movement of one shoe when the crank-arm and block have no movement in the direction of the length of the crank-shaft.

In Figs. 4, 5, and 6 I have shown a modification of my invention applicable to a press wherein the shoe has a swinging movement—such, for instance, as in United States Patent No. 322,309, dated July 14, 1885. The rack-driving gear D^x is mounted on a hollow shaft 85 or sleeve D¹⁰, rotatable in suitable bearings I, substantially as in said patent, the shaft being rotated by means of a pinion K fast thereon. The sleeve is raised and lowered by suitable devices to bring the gear D^x into alternate engagement with two racks (not shown) above and below it and carried by the bed of the press. A shaft f^x, extended through the sleeve D¹⁰, has secured thereto adjacent the outer face of the gear D^x a pinion f, the other end of said shaft being shown as squared at f' to enter a slot h in the head of a standard H, said slot being shown in Fig. 6 as slightly inclined to correspond with the path of the movement of the sleeve D¹⁰ when it is raised 100 and lowered. The shaft f^x is thus held from rotation while the sleeve is free to be rotated. An intermediate pinion m, in mesh with pinion f, is rotatably mounted on a suitable stud m^x, carried by the gear D^x, and on a foot d¹⁰, secured to said gear, is attached a pin n^x, on which is rotatably mounted the actuating-block G¹⁰, having an attached pinion n in mesh with the intermediate m, the pinion n being of the same diameter as the pinion f. 110 When the gear D^x is rotated, the parallel bearing-faces of the block G¹⁰ will thus be maintained in parallelism with the co-operating faces of the shoes, (not shown,) one of the shoes being adapted to be swung to one 115 side in the patent referred to to remove it from the path of the block when the latter is about to enter or leave the guideway between the shoes. A collar f² on the end of the shaft f^x outside of the standard H prevents longitudinal movement of said shaft.

I have shown two applications of my invention, and it will be obvious that I am not restricted to the particular means employed for permitting the entrance and departure of the actuating-block from between the shoes at the beginning and end of the reversing movement, the gist of my invention consisting, essentially, in the use of a plane-faced actuating-block and means for maintaining it in proper position relative to the devices with which it intermittently cooperates.

Having fully described my invention, what I claim as new, and desire to secure by Letters Patent, is—

1. In a bed-motion for printing-presses wherein the bed is reciprocated, a guideway carried by and at right angles to the bed, a reversing member movable in a circular path and having a plane bearing-face, to coöperate intermittently with said guideway, and means 5 to position the bearing-face of said member to enter the guideway.
2. In a reversing mechanism, a reciprocating member, a guideway mounted thereon, a reversing member movable in a circular path 15 and having a plane bearing-face, to coöperate intermittently with the guideway, and means to position the bearing-face of said member to enter the guideway.
3. In a reversing mechanism, a reciprocating member, relatively movable shoes carried thereby to form a guideway, a reversing member movable in a circular path and having parallel plane bearing-faces, to enter said guideway intermittently and coöperate with 25 the shoes, means to position the bearing-faces of said reversing member to enter the guideway, and means to effect relative movement of the shoes to permit the entrance to and departure of the reversing member from the 30 guideway.
4. In a reversing mechanism, a rotating carrier, a rotatable reversing member mounted eccentrically thereon and having a plane bearing-face, a member to be reversed, with 35 which the reversing member engages intermittently, and means to effect axial rotation of said reversing member during the movement thereof in a circular path to thereby maintain the bearing-face in parallel planes 40 throughout the circular path and in position to coöperate with the member to be reversed.
5. In a reversing mechanism, a revolving carrier, a rotatable plane-faced reversing member mounted thereon and having an attached pinion, a fixed pinion centrally mounted 45 relative to the carrier, and an intermediate pinion rotatable on the carrier and in mesh with said fixed and reversing-member pin-

ions, to effect rotation of the said member relatively to the carrier as the latter revolves. 50

6. In a printing-press, a reciprocating bed and parallel guideways carried thereby, means to reciprocate the bed, and reversing mechanism for the bed, including a plane-faced actuating member movable in a circular path, means to maintain the acting faces thereof in parallelism with the guideways, with which latter it coöperates alternately to reverse the bed, and means to move the reversing member into and out of said guideways at 60 the beginning and ending of the reversing movement.

7. In a reversing mechanism, a rotatable hollow shaft or sleeve, a crank-arm carried thereby, a stationary pinion adjacent the face 65 of said arm and mounted on a fixed shaft extended through the sleeve, an actuating member having an attached pinion and rotatable on said crank-arm, said member having plane acting faces, and an intermediate pinion 70 rotatably mounted on the crank-arm and in mesh with the fixed and actuating-member pinions, to maintain the plane faces of said member parallel to a fixed plane throughout the revolution of the crank-arm. 75

8. In a reversing mechanism for printing-presses wherein a bed having attached parallel guideways at the ends thereof is reciprocated, a rotatable, longitudinally-movable shaft, a crank-arm thereon, an actuating 80 member rotatably mounted thereon and having parallel acting faces, means to move the sleeve longitudinally to effect coöperation of the said member intermittently with the guideways, and means mounted on the crank-arm to maintain the faces of the actuating member in parallelism with the guideways 85 throughout the revolution of the crank-arm.

In testimony whereof I have signed my name to this specification in the presence of 90 two subscribing witnesses.

WILLIS K. HODGMAN.
